LOCK FOR A SWINGING WINDOW PANEL

Emory Glenn Simpson, Detroit, Mich., assignor
to Ternstedt Manufacturing Company, De-
troit, Mich., a corporation of Michigan

Application August 23, 1935, Serial No. 37,425

9 Claims. (Cl. 296—44)

This invention relates to a lock for a swinging window panel, and more particularly the invention relates to a lock for locking both the swinging window panel and the window regulator by means of which the panel is operated.

In the case of ventilating automobile windows which includes a panel which can be swung about a vertical axis for ventilating purposes, thieves sometimes gain entry to the automobile by prying the window slightly open and inserting a suitable instrument, such as a wire with a loop or hook on the end, through the opening to engage the regulator handle and turn the handle to swing the panel further open. This permits access to the inside door latch handle which is operated to retract the latch bolt and thus open the door.

It is an object of this invention to produce a thief-proof lock for this type of swinging window and which, among other things, will thwart entry into an automobile by the above-mentioned manner.

In the drawings:

Fig. 1 is a fragmentary side elevation of a ventilating window assembly in which the swinging window and regulator are provided with a lock which is the subject matter of this invention.

Fig. 2 is an assembly view showing the lock and swinging panel.

Fig. 3 is a detail of the lock and swinging window panel regulator.

Fig. 4 is a vertical section through the window and door showing the window in locked position.

Fig. 5 is a detail of the support plate for the window glass lock.

Figs. 6, 7 and 8 are details of the window glass locking mechanism.

In the drawings the locking device is shown applied to the swinging panel 1 of the well-known Fisher no draft ventilating window used on General Motors cars. In this type of window assembly, for example, the window opening 2 of the front vehicle door 3 is arranged to be closed by the front swinging panel 1 and the rear panel 4 which slides up and down, out of and into the window well in the well-known manner. The front swinging panel 1 is pivoted as at 5 and 6 to swing about a vertical axis between its front and rear vertical edges.

The lower pivot 6 takes the form of a shaft which is coupled to a worm gear 7 mounted in the window regulator housing 8. The gear 7 is meshed with, and driven by, a worm 9 carried on the spindle 10. A suitable regulator handle 11 is fixed on the inner end of the spindle 10. By

turning the handle 11, which acts through the spindle 10, worm 9, gear 7 and shaft 6, the window panel 1 may be swung to open or closed position.

The pitch of the worm 9 and worm gear 7 is such that the action is self-locking or irreversible, that is, the worm 9 and handle 11 cannot be driven by force applied to the swinging panel 1. However, there is a small amount of play between the worm 9 and the gear 7. This sometimes may permit the panel 1 to be pried open a slight distance. Then, too, the panel 1 projects a sufficient distance in back of the pivots 5 and 6 that there is sufficient spring in the glass panel 1 and the metal channel frame 12 in which the panel 1 is mounted to permit the panel to be sprung slightly open when pressure is applied by means of a suitable instrument to the channel 12 adjacent the rear vertical edge of the panel. While the window panel is pried open a slight distance, a wire with a loop or hook on the end can be inserted and the regulator handle 11 turned to swing the panel further open a sufficient distance to obtain access to the interior of the vehicle body. To prevent this and other possible ways of obtaining access to the interior of the car through the swinging panel, it is proposed to lock both the swinging panel and its operating regulator in closed position. Preferably both the lock for the regulator and the swinging window panel are coincidentally operated through a single handle.

For locking the swinging panel 1 there is provided a bolt 13 which is vertically reciprocable in the bolt casing 14. The casing 14 is supported by plate 15 which is secured by the screws 16 to the belt rail 17 in the window well. The bolt 13 is provided with an opening 18 for the stud 19. The stud 19 is fixed to the bolt 13, such as by upsetting the end of the stud 19 in the opening 18. The stud 19 passes through an elongated opening 20 in the bolt casing 14 which permits the stud 19 to travel back and forth with the bolt 13.

A latch operating lever handle 21 is pivotally mounted on the bolt casing 14 by the pivot pin 22. The lever handle 21 is provided with a cam opening 23 through which the stud 19 passes and in which it engages the lever handle 21. A coil spring 24 is mounted over the stud 19 between the headed end of the stud and the handle 21. The lever handle 21 is provided with a raised rib 25 at each end of the cam slot 23. When the lever is swung so that the stud 19 reaches either end of the cam slot 23, the spring 24 is compressed by the rib 25 thereby yieldably holding

the lever handle 21 in either locking or unlocking position.

It will be noted that, as viewed in Figs. 2 and 8, the lower end 26 of the cam slot 23 is closer to the center of rotation, namely, the pin 22 about which the lever swings, than the upper end 27 of the slot 23. Thus, when the panel 1 is in closed position and the lever handle 21 is swung counterclockwise the cam slot 23, acting through the stud 19, retracts the latch bolt 13 from the bolt opening 27 in the channel 12 and when the handle is swung clockwise from the dotted line position, the bolt 13 is projected upwardly into engagement with the opening 27 in the channel 12.

15 The garnish molding 28 is provided with a slot 29 through which the lever handle 21 swings during operation. The outer end of the lever handle 21 is provided with a finger piece 30. A wear plate 31 provided with an outwardly pressed rib 32 is riveted or otherwise fixed to the top of the support plate 15. This wear plate 31 is positioned between the rubber weatherstrip 33 for the swinging window panel 1 and the lever handle 21. The rib 32 is slidably engaged by the inside 25 face of the lever handle 21 and guides the same when swung about its pivot 22.

For locking the window regulator a toothed gear or ratchet 34 is fixed upon the spindle 10 within the regulator gear housing 8. An opening 35 is provided in the side wall of the housing 8. A locking pawl 36, provided with an enlarged head 37, is supported in the opening 38 in the lug 41 at the bottom of the lever 21. The other end of the pawl 36 projects through the opening 35 in the regulator casing 8 and is supported therein, a suitable anti-rattling spring 39 being mounted between a wall of the opening and the pawl 36.

It will be noted that the pawl 36 has a lost motion connection with the bottom of the lever handle 21 in the opening 38. A coil spring 40 and washer 42 are mounted between the lug 41 of the lever handle and the pressed out ears 43 on the pawl 36. If the pawl dentally engages one of the teeth of the ratchet 34, then as soon as the handle 10 and ratchet 34 are turned, the pawl will ride out of dental engagement with the tooth and the spring 40 will cause the pawl to snap into locking engagement with the ratchet between this and the next tooth.

50 In operation it will be noted that as shown in the full lines, Fig. 2, the regulator is locked through the pawl 36 and ratchet 34 and the window panel 1 is locked by the interengagement of the bolt 13 and the keeper opening 21 in the channel 12. To release both the regulator and the window panel the lever handle 30 is swung counterclockwise as indicated by the arrow to the dotted line position. This, as described above, 55 retracts the bolt 13 and the lug 41 engages the head 37 of the pawl 36 to retract the other end of the pawl from engagement with the ratchet 34.

If the panel 1 is swung to any open position and the lever handle 20 swung to the full line position shown in Fig. 2, the pawl 36 will engage the ratchet 34 to lock the regulator and project the bolt 13. However, since the regulator is dogged by the pawl 36, the window panel 1 cannot be closed. Therefore this arrangement positively prevents swinging the panel 1 closed when the bolt 13 is projected which would cause the panel to collide with the bolt and damage either or both.

75 If the window glass 1 is slightly open so that the channel frame 12 is offset from the bolt 13

and the operator throws the lever 30 to the full line position, Fig. 2, to lock the regulator it may be that the pawl 36 will dentally engage one of the teeth of the ratchet 34. However, this will make no difference because if a thief now inserts a looped wire through the opening caused by the slightly opened window glass 1 to engage the regulator handle 11 and turn the same the pawl 36 will ride off the ratchet tooth with which it is dentally engaged into the valley between the two consecutive teeth thus dogging the handle against further rotation.

I claim:

1. In an automotive vehicle the combination with a swinging window panel and a regulator for swinging the said panel, of a reciprocable latch bolt for locking said regulator when the window panel is opened as well as when the window panel is closed, a reciprocable latch bolt separate from said above-mentioned latch bolt for locking said panel only in closed position, and a single means for reciprocating said bolts to locked or unlocked position.

2. In an automotive vehicle the combination with a swinging window panel and regulator including a rotatable handle and spindle for swinging the said panel, of a toothed member fixed on the said spindle, a keeper member mounted on the said window panel, a pair of reciprocable latch bolts one of which is adapted to engage the toothed member to lock the window regulator and the other of which is adapted to engage the keeper to lock the said panel, and means for simultaneously operating both of said bolts to lock or unlock the said regulator and panel.

3. In an automotive vehicle having a swinging window panel and a regulator for swinging the said panel, the combination comprising a reciprocable latch bolt for locking said regulator, a reciprocable latch bolt for locking said panel, a reciprocable handle member separate from said latch bolts, operative connections between the reciprocable handle member and said bolts whereby the said handle member may be reciprocated to simultaneously project or retract the said bolts into and out of locking engagement with the said regulator and panel.

4. In a vehicle having a swinging window panel and a regulator for swinging the said panel, the combination comprising a reciprocable latch bolt for locking said regulator, a reciprocable latch bolt for locking said panel, a pivoted handle member having a cam connection with the bolt for locking the window panel, and a separate connection with the bolt for locking the regulator whereby swinging of the pivoted lever handle simultaneously operates the said bolt members.

5. In a vehicle body having a window opening and a well therebelow, a window panel mounted in the said opening to swing about a vertical axis, a regulator positioned in the said well for swinging said panel, locking mechanism for the said panel and regulator mounted in the said window well and comprising a vertically reciprocable bolt and a horizontally reciprocable bolt, and a lever handle mounted to swing about a horizontal axis having a finger portion projecting above the mouth of the window well, operative connections between the said lever handle and bolts whereby the lever handle may be swung to project the said bolts into locking relation with the said panel and regulator.

6. In a vehicle body having a window opening and a well therebelow, a window panel mounted in the said opening to swing about a vertical axis,

a regulator positioned in the said well for swinging said panel, locking mechanism for the said panel and regulator mounted in the said window well and comprising a vertically reciprocable bolt 5 and a horizontally reciprocable bolt, a lever handle mounted to swing about a horizontal axis having a finger portion projecting above the mouth of the window well, a bolt keeper carried by the said swinging panel, a cam slot 10 and pin connection between the lever handle and the vertically reciprocable bolt, and an operative connection between the lever handle and the horizontally reciprocable bolt whereby when the window panel is closed the said lever handle 15 may be pivoted to throw the one bolt into engagement with the said keeper to lock the window panel and the other bolt into locking engagement with the said regulator.

7. In a vehicle body having a window opening 20 and a well therebelow, a window panel mounted in the said opening to swing about a vertical axis, a regulator positioned in the said well for swinging said panel, locking mechanism for the said panel and regulator mounted in the said window well and comprising a vertically reciprocable bolt 25 and a horizontally reciprocable bolt, a lever handle mounted to swing about a horizontal axis having a finger portion projecting above the mouth of the window well, a bolt keeper carried 30 by the said swinging panel, a cam slot and pin connection between the lever handle and the vertically reciprocable bolt, and an operative connection between the lever handle and the horizontally reciprocable bolt, the said regulator including a rotatable handle and spindle, a ratchet 35 fixed on the said spindle within the window well, a wear plate positioned in the window well provided with a rib arranged to be slidably engaged by the said lever handle when it is swung about its pivot to throw the said bolts into locking engagement with the said window panel keeper and ratchet to lock the panel and regulator.

8. In a vehicle body having a window opening and a well therebelow, a window panel mounted in the said opening to swing about a vertical axis, a regulator positioned in the said well for swinging said panel, locking mechanism for the said panel and regulator mounted in the said window well comprising a vertically reciprocable bolt and a horizontally reciprocable bolt and a lever handle mounted to swing about a horizontal axis having a finger portion projecting above the mouth of the window well, a bolt keeper carried by the said swinging panel, a cam slot and pin connection between the lever handle and the vertically reciprocable bolt, and an operative connection between the lever handle and the horizontally reciprocable bolt, the said regulator including a rotatable handle and spindle, a ratchet 10 fixed on the said spindle within the window well, a wear plate positioned in the window well provided with a rib arranged to be slidably engaged 15 by the said lever handle when it is swung about its pivot to throw the said bolts into locking engagement with the said window panel keeper and ratchet to lock the panel and regulator.

9. In combination with a swinging window 25 panel and a regulator including a rotatable spindle for swinging the said panel, a ratchet fixed on the said spindle, a reciprocable latch bolt for locking the said regulator, a reciprocable latch 30 bolt for locking the said panel, a swingable lever handle, operative connections between the said bolts and lever handle including a lost motion spring connection between the lever handle and the bolt for locking the regulator whereby when 35 the lever handle is operated to project the bolts into locking position and the one bolt dentally engages the said ratchet, upon rotation of the said spindle and ratchet, the said spring will project said bolt into locking engagement with the 40 said ratchet.

EMORY GLENN SIMPSON.
